UNITED STATES PATENT OFFICE.

CHARLES S. CRICKMER, OF DALLAS, TEXAS, ASSIGNOR TO THE GUIBERSON CORPORATION, OF DALLAS, TEXAS, A CORPORATION OF DELAWARE.

DEFLECTOR AND SCRAPER FOR WELL APPLIANCES.

Application filed March 3, 1925. Serial No. 12,888.

This invention relates to new and useful improvements in deflectors and scrapers for well appliances.

In placing tubing catchers in well casings considerable difficulty is often experienced due to the formation of paraffin on the walls of the casing, which reduces the diameter. Another source of trouble is occasioned by a head pressure of oil and the like, which tends to displace the weight and set the slips.

The object of the invention is to provide a device which may be attached to a tubing catcher or other appliance whereby the paraffin coating will be scraped from the walls of the well casing as the catcher is raised and lowered in the well.

A particular object of the invention is to provide a deflector for installation below the weight of a tubing catcher or other device arranged to deflect a liquid and cause it not only to take a sinuous or helical course, but to break up the fluid into numerous streams; whereby the head pressure is reduced and the weight saved from displacement.

A further object is to provide a deflector having helical vanes or flanges surrounding a tubular support and preferably provided with vertical flat cutting edges forming scrapers.

A construction designed to carry out the invention will be hereinafter described together with other features of the invention.

The invention will be more readily understood from a reading of the following specification and by reference to the accompanying drawings, in which an example of the invention is shown, and wherein:

Fig. 1 is a plan view of a device constructed in accordance with my invention,

Figure 2 is an elevation of the same, the lower end of the sleeve being illustrated in section, and Fig. 3 is an elevation of a tubing catcher equipped with a deflector and scraper constructed in accordance with my invention.

In the drawings the numeral 10 designates a sleeve which is internally threaded at each end. Beginning at the upper end of the sleeve are a plurality of vanes or flanges 11 coiled helically around the sleeve and preferably terminating at a substantial distance from the bottom of the sleeve. These vanes are shown as equally spaced,

but this is not essential. While the vanes are shown as integral with the sleeve it is within the scope of the invention to form them otherwise.

The vanes have flat vertical outer edges 12 which function as scrapers when the deflector is moved vertically in the casing. The ends 13 of the vanes are rounded so as to obviate sharp corners which would catch; also the rounded corners facilitate the entrance of the deflector into the casing. I have shown four vanes, but the number is subject to variation.

That portion of the sleeve extending below the vanes constitute a collar 14 which provides means for applying a wrench to the device. The upper end of the sleeve is screwed onto the lower end of the lower pipe section 15 of a tubing catcher or other well appliance as is shown in Fig. 3 and the collar 14 receives the tubing (not shown) below the deflector. The coiled spring 16 of the catcher rests upon the sleeve 10.

As the catcher is lowered into the well casing the edges 12 of the deflector will scrape the paraffin and other accumulations from the inner walls of the well casing, the deflector being slightly less in diameter than the inner diameter of the casing. When liquid, such as oil is encountered it will be deflected into the four helical channels formed between the vanes 11. The deflector is mounted below the weight 17 of the tubing catcher and the liquid being thus deflected and broken into streams will be retarded or diverted sufficiently to prevent dislodging the weight or setting the slips. The deflector permits the catcher to move freely down the wall against a head pressure of fluid.

The deflector is particularly adapted for use in connection with tubing catchers of the type shown in Patent No. 1,218,549, but may be used on any type where it is found advantageous.

Various changes in the size and shape of the different parts, as well as modifications and alterations may be made within the scope of the appended claims.

What I claim, is:

1. The combination with a tubing catcher having a resiliently sustained weight, of a fluid deflector mounted on said catcher below its weight and having a helical chan-

nel in its outer surface for deflecting fluid in advance of said weight as said catcher moves downwardly in the well.

2. The combination with a tubing catcher 5 having a resiliently sustained weight, of a fluid deflector comprising a sleeve and a helical channel outside of said sleeve, said sleeve being mounted on said catcher below the weight thereof for deflecting fluid in 10 advance of said weight as said catcher moves downwardly in the well.

3. The combination with a tubing catcher 15 having a resiliently sustained weight, of a fluid deflector mounted on said catcher below its weight and having a helical vane extending vertically thereof for deflecting fluid in advance of said weight as said catcher moves downwardly in the well.

4. The combination with a tubing catcher 20 having a resiliently sustained weight, of a fluid deflector mounted on said catcher below its weight and having a plurality of helical channels in its outer surface, each channel extending vertically and open at 25 its upper and lower ends for deflecting a fluid into streams offering negligible resistance to the weight as the catcher moves down the well.

5. The combination with a tubing catcher 30 having a resiliently sustained weight, of a fluid deflector mounted on said catcher below the weight thereof and having a plurality of helical vanes on its outer surface, each vane extending vertically and forming 35 with the other vanes helical channels open at their upper and lower ends for deflecting

a fluid into streams in advance of said weight as the catcher moves downward in the well.

6. The combination with a tubing catcher 40 having a resiliently sustained weight, of a fluid deflector comprising a central sleeve, and a plurality of helical vanes disposed vertically on said sleeve, said sleeve being attached to the lower end of the catcher 45 below the weight thereof for deflecting the fluid into streams in advance of said weight as the catcher moves downward in the well.

7. The combination with a tubing catcher 50 having a resiliently sustained weight, of a deflector comprising a central sleeve, and a plurality of helical vanes disposed vertically 55 in said sleeve and having outer scraping edges, said sleeve being attached to the catcher below said weight for deflecting the fluid into streams and scraping the paraffin from the walls of the well in advance of the weight.

8. The combination with a tubing catcher 60 having a resiliently sustained weight, of a deflector comprising a central sleeve, and a plurality of helical vanes disposed vertically 65 in said sleeve and having flat outer scraping edges, said sleeve having a downwardly extending collar attached to the catcher below said weight for deflecting the fluid into streams and scraping the paraffin from the walls of the well in advance of the weight.

In testimony whereof I affix my signature.

CHARLES S. CRICKMER.
